3905

Alphabet of letters styled Olden Ornamental
W.H. Page

PATENTED MAR 15 1870

United States Patent Office.

Design No. 3,905, dated March 15, 1870.

DESIGN FOR TYPE.

The Schedule referred to in these Letters Patent and making part of the same

To all whom it may concern:

Be it known that I, WILLIAM H. PAGE, of the town of Norwich, in the county of New London, and State of Connecticut, have invented or produced a new and original Design of Letter for Printing Purposes, styled "Aldine Ornamented," for letter-press printing; and I do hereby declare that the accompanying drawing is a full and exact representation of the same, the two alphabets to be printed single, or the one printed over the other in colors.

What I claim, and desire to secure by Letters of Patent, is—

The design for the two alphabets of letters, as shown and described.

WM. H. PAGE.
